STATIC PRESSURE VALVE

George T. Downey, Corry, Pa., assignor to Aero Supply Manufacturing Co., Inc., Corry, Pa.

Application June 7, 1939, Serial No. 277,920

8 Claims. (Cl. 277—20)

This invention relates to valves, and more particularly to a valve structure for controlling the passage of a fluid through selected ports.

An object of this invention is to provide a manually operable valve structure including a housing provided with a plurality of intake ports, a single outlet port, a chamber common to all of the ports and a valve carrier shiftable into engagement with a selected intake port to close the same, the carrier being yieldably held in port closing position.

Another object of this invention is to provide a control valve designed particularly for use in airplane structures for controlling the source of air or fluid pressure to pressure operated instruments.

A further object of this invention is to provide a controlling valve for use in airplane structures for controlling the source of fluid pressure to pressure operated instruments, the valve structure including a swingable valve carrier and cooperating means carried by the carrier and the valve housing for holding the carrier against rotary movement while permitting swinging movement thereof to a port closing position.

A still further object of this invention is to provide in a structure of this kind an improved operating means for shifting the valve and carrier to a port closing position, the operating means being provided with a luminous means so that the operator may be engaged in the dark.

A further object of this invention is to provide in a valve structure of this kind an improved means for yieldably holding the valve and carrier in a port closing position, this latter means including a rockable spring pressed pin engaging in a suitable socket provided in the housing so as to permit rocking movement of the pin cooperative with the swinging movement of the valve carrier.

To the above objects and to others which may hereinafter appear, the invention consists of the novel construction, combination and arrangement of parts as will be more specifically referred to and illustrated in the accompanying drawings, but it is to be understood that changes, variations and modifications may be resorted to which fall within the scope of the invention as claimed.

In the drawings:

Figure 1 is a detail front elevation of a valve structure constructed according to an embodiment of this invention.

Figure 2 is a detail rear elevation partly in section of the device.

Figure 3 is a sectional view taken on the line 3—3 of Figure 1.

Figure 4 is a sectional view taken on the line 4—4 of Figure 1, the valve operator being shown in a central position.

Figure 5 is a plan view of the inner portion of the valve housing.

Figure 6 is a detail side elevation of one of the carrier operating members, and

Figure 7 is a detail side elevation of another of the carrier operating or holding members.

Figure 8 is a detail side elevation of the valve carrier partly broken away and in section.

Referring to the drawings, the numeral 10 designates generally a housing comprising an inner part 11 and an outer part 12 secured together by means of bolts or screws 13 which in the present instance extend through the inner part 11 and are threaded into the outer part 12. A gasket 14 is interposed between the confronting faces of the two housing parts 11 and 12 which are preferably, held against lateral movement relative to each other by means of spotting pins 15 carried by the inner member 11 which are engageable in sockets 16 carried by the outer member 12.

The inner housing member 11 is provided with a pair of spaced apart fluid ports 17 and 18 which communicate at their inner ends with fluid passages 19 and 20 respectively. A fluid pipe line 21 is adapted to be threaded into the port 17 and a second fluid pipe line 22 is adapted to be threaded into the port 18. These pipe lines 21 and 22 are connected at their opposite ends to a fluid source which may be either air under pressure or other suitable fluid. A central port 23 is provided intermediate the two ports 21 and 22 and a pipe 24 is threaded into the port 23. This port 23 is preferably an outlet port and the ports 17 and 18 are preferably inlet ports. A passage 25 is provided in the inner housing member 11 which communicates at its outer end with the outlet port 23 and communicates at its inner end with a fluid chamber 26 provided on the interior of the housing 10.

The outer housing member 12 is provided with a fluid passage 27 which at one end communicates with the fluid passage 19. An angularly disposed fluid passage 28 is provided in the outer member 12 and this angularly disposed passage 28 communicates at one end with the outer end of the passage 27 and at the opposite or inner end communicates with the common chamber 26. The outer housing member 12 is also provided with a fluid passage 29 communicating at its inner end with the outer end of the fluid passage 20 and a second or angularly disposed passage 30.

39 is provided in the outer member 12 which communicates at its outer end with the outer portion of the fluid passage 29. The inner end of the fluid passage 30 communicates with the common or central chamber 26 at a point opposite from the passage 28.

5 The outer housing member 12 is provided with a valve seat 31 which is disposed at substantially right angles to the axis of the passage 28 and a second or opposite valve seat 32 is provided on the opposite side of the housing 12 about the passage or duct 30. A valve member comprising a valve head 33 and a gasket 34 which is secured to the head 33 by means of a washer 35 which is disposed on a reduced extension 36 is disposed in the chamber 26. The extension 36 is upset to tightly secure the washer 35 against the outer or operating face of the gasket 34. The washer 35 is substantially smaller in diameter than the 10 diameter of the passage 28 so that when the valve member comprising the head 33 and the gasket 34 are in port closing position the washer 35 will loosely engage within the inner end of the passage 28. The valve head 33 has a stem 37 secured thereto and the stem 37 may if desired, be formed integrally with the head 33. The stem 37 loosely engages in a socket 38 provided in a valve carrier 39. The stem 37 is held loosely within the socket 38 by means of a pin 40 which may have the opposite ends thereof upset so as to hold the pin 40 against endwise movement.

15 The carrier 39 has a second socket 42 diametrically opposite from the socket 38 in which a valve stem 43 loosely engages. The valve stem 43 is held against removal from the socket 42 by means of a pin 44 provided with upset opposite end portions to hold the pin 44 against endwise movement. The valve head 45 is carried by the stem 43 and a gasket 46 engages against the outer face of the head 45. A washer 47 is riveted or otherwise secured to the stem 43 as at 48 and the washer 47 is adapted when the carrier 39 is on the side opposite from that shown in Figure 3 to engage within the passage 30 in the same manner as the washer 35.

20 The carrier 39 is moved to a port closing position by means of an operating lever generally designated as 49 which comprises a handle 50 having a luminous outer end portion 51. A substantially spherical member 52 is carried by the operator 49 and engages a socket or seat 53 formed in the outer wall 54 of the outer housing 12. The lever or operator 49 projects outwardly through the opening formed by the seat 53. An annular sealing member 55 is mounted in a recess 56 formed in the outer wall 54 and a holding plate 57 engages against the sealing member 55 and is tightly held against the sealing member 55 by means of a split clamping ring 58 which engages in an annular groove 59 formed in a boss 60 on the inner side of the wall 54. A stud 61 is formed integrally with the spherical member 52 and a reduced extension 62 is carried by the stud 61 and projects loosely into a socket or recess 63 formed in the valve carrier 39. In this manner rocking of the handle or operator 49 with the ball 52 as a fulcrum will swing the valve carrier 39 to the desired port closing position.

25 The valve carrier 39 is provided on its inner side with a slide member or lug 64 which engages in the arcuate guide channel 65 formed in the inner side of the inner housing member 11 as shown in Figure 3. The outlet port 25 as shown in Figure 4 communicates with the common chamber 26 through the guide channel 65. By

means of the slide member 64 the carrier 39 is held against axial rotation with respect to the operator 49 but is permitted to have swinging movement with the operator 49 so as to close a selected port upon rocking of the operator 49.

30 The carrier 39 is held in the selected port closing position by means of a pair of springs 66. The springs 66 are disposed on opposite sides of the slide or guide member 64 and each spring 66 loosely engages about a sleeve or cylindrical member 67 which at its outer end is provided with a right angularly disposed opening 68 within which a laterally projecting stud 69 carried by the carrier 39 engages. A rockable pin 70 is slidably in an opening 71 formed in the sleeve 67 and the pin 70 is provided with a shoulder or plate 72 which is positioned intermediate the ends of this pin. The inner end of the pin 70 is provided with a semi-spherical head or bearing member 73 which is adapted to engage in a concave socket 74 provided on the inner wall 75 of the inner housing member 11. The inner wall 75 is also provided about the socket 74 with a recess 76 within which the marginal portions of the washer 12 may engage as shown in Figure 3. The spring 66 engages at one end against the washer 72 and at the other end against a shoulder 77 formed on the inner end of a head 78 which is carried by the sleeve 67. The opening 68 engages through the head 78. There are two studs 69 on the carrier 39 which are disposed in opposite directions and two springs 66 which engage a pair of sleeves 67 within which pins 70 slidably engage as shown in Figure 4.

35 The sockets 74 for the pins 70 are disposed in alignment with the axis of the spherical member 52 so that when the operator 49 is rocked the springs 66 will be disposed in angular relation with respect to the axis of the spherical member 52 and thus hold the carrier 39 in the selected 40 port closing position. A face plate 79 is secured to the outer face of the outer member 12 by means of screws or bolts 80 and preferably a supporting member 81 is adapted to engage between the face plate 79 and the outer housing member 45 12. The plate 79 is provided with a substantially round opening 82 in the center thereof and laterally and oppositely projecting openings 83 extending from the opening 82 and within which the inner end of the handle 50 is adapted to engage as shown in Figure 3. The face plate 79 may be provided on one side thereof with indicia 84 and on the opposite side with indicia 85 which are co-related with the intake ports 17 and 18 so that the user of the device will be able to determine with which source of supply the housing 10 is in communication.

40 In the use and operation of this valve structure, the ports 17 and 18 are adapted to be connected to a suitable source of fluid supply under pressure and the outlet port 23 is adapted to be connected to the desired element which is acted on by the fluid passing through the housing 10. It will be appreciated that if desired the direction of the fluid through the housing 65 60 may be reversed, that is, the two ports 17 and 18 may be used as outlet ports and the port 23 used as an inlet port which is connected to a source of fluid supply under pressure. In the present instance, the pipe 24 connects the housing 10 with a pressure operated instrument structure receiving fluid pressure through one of the intake pipes 21 or 22.

45 Assuming that it is desired to receive the fluid pressure from the intake pipe 22, the valve car- 75

rier is swung as shown in Figure 3 to the left by means of the operator 49 so that the valve structures 33 and 34 will engage against the valve seat 31. In this position of the carrier, the intake port 17 is cut off from communication with the common chamber 26 and the fluid passages 20, 29 and 30 connect the intake port 18 with the chamber 26 so that the fluid can flow from the intake port 18 through the pipe 23 into the chamber 26 and then out through the outlet passage 25 and the outlet pipe 24. The springs 66 will yieldably hold the valve carrier 39 in the selected port closing position.

In the event it is desired to change the source of fluid supply the handle or operator 49 is rocked in the opposite direction, the carrier 39 swinging to the right with the slide member 64 slidably engaging in the channel 65. The swinging movement of the carrier 39 will bring the two springs 66 on the opposite side of the axial center or fulcrum of the operator 49 so that the valve structure comprising the head 45 and the gasket 46 will be yieldably held against the valve seat 32. During the rocking of the valve carrier 39 from one valve seat to the other, the pin 70 will at its inner end 73 rock in the socket 74. This pin 70 will at all times be held in axial relation with respect to the sleeve 64.

A valve structure of this kind is an exceedingly simple and practical valve structure which due to the manner of assembly cannot be assembled incorrectly. This is due to the fact that the slide member 64 will hold the valve carrier 39 against axial rotation with respect to the operator 49 so that the two valve members carried by the valve carrier 39 will be in a proper position for engagement with the selected valve seat upon swinging of the carrier 39. The two housing parts 11 and 12 are held against sliding movement relative to each other during the assembly thereof by means of the spotting pins 15 which engage in the sockets 16 of the outer housing member.

While this valve structure has been designed particularly for use in controlling the source of air pressure to air pressure operated instruments on airplanes, it will be apparent that a structure of this kind can readily be adapted for use with other devices of fluid including liquids.

What I claim is:

1. A valve comprising a housing provided with at least three fluid ports and a chamber common to all of said ports, a valve seat formed about two of said ports in said chamber, a valve carrier in said chamber, oppositely disposed valves carried by said carrier, a carrier operating lever engaging said carrier and rockably carried by said housing, and yieldable means in said chamber engaging said housing and said carrier for holding said carrier in a selected port closing position, said yieldable means including a part carried by the carrier, a part rockably engaging said housing and a spring between said parts.

2. A valve comprising a housing provided with at least three fluid ports and a chamber common to all of said ports, a valve seat formed about two of said ports in said chamber, a valve carrier in said chamber, oppositely disposed valves carried by said carrier, a carrier operating lever engaging said carrier and rockably carried by said housing, a pair of oppositely directed studs carried by said valve carrier, a sleeve rockably carried by each stud and disposed at right angles relative to said studs, a pin slidable in each sleeve, said housing having a rounded pin receiving

socket, each pin having a rounded end engaging in a socket, a shoulder carried by each pin, a shoulder carried by each sleeve, and a spring engaging about each sleeve between the shoulder on the sleeve and the shoulder on the pin and yieldably holding said carrier in a selected port closing position.

3. A valve comprising a housing provided with at least three fluid ports and a chamber common to all of said ports, a valve seat formed about at least two of said ports in said chamber, a valve carrier in said chamber, a pair of oppositely disposed valves, means securing said valves to said carrier in a manner whereby said valves may have limited movement relative thereto, a carrier operating lever rockably carried by said housing, said carrier having an opening therein, an extension carried by said lever engaging in said opening, and yieldable means engaging the housing and the carrier for holding the carrier on said extension while simultaneously holding said carrier in a selected port closing position.

4. A valve comprising a housing provided with at least three fluid ports and a chamber common to all of said ports, a valve seat formed about at least two of said ports in said chamber, a valve carrier in said chamber, the wall of said chamber having a portion thereof constituting a guide means for the carrier, a pair of valve members, a stem carried by each member having a transverse opening, said carrier having a pair of oppositely disposed openings, said stems loosely engaging in said openings in said carrier, a pin engaging through said carrier and through the stem opening to hold the stem against endwise movement while permitting a limited swinging movement, a carrier operating lever rockably carried by said housing and engaging said carrier, and means yieldably holding said carrier in a selected port closing position.

5. A valve comprising a housing provided with at least three fluid ports and a chamber common to all of said ports, a valve seat in said chamber formed about at least two of said ports, a valve carrier in said chamber, guide means for said carrier, oppositely directed valves carried by said carrier, a carrier operating lever, a spherical bearing member carried by said lever, a bearing seat carried by said housing, a ring-shaped sealing member engaging against said bearing member, a washer bearing against said sealing member, a boss carried by said housing projecting inwardly of said bearing seat and provided with an annular groove, and a locking ring engaging in said groove and bearing against said washer.

6. A valve comprising a housing provided with at least three fluid ports and a chamber common to all of said ports, a valve seat in said chamber formed about at least two of said ports, a valve carrier in said chamber, oppositely directed valves carried by said carrier, a carrier operating lever rockably carried by said housing, means mounting said carrier on said lever, means yieldably holding said carrier in a selected port closing position, an arcuate guide means carried by said housing, and a slide member fixed to said carrier and engaging said guide means to hold said carrier against axial movement relative to said lever.

7. A valve comprising a housing provided with at least three fluid ports and a chamber common to all of said ports, a valve seat formed about two of said ports in said chamber, a valve carrier in said chamber, means swingably mounting said

carrier in said housing, said means including an operating lever projecting exteriorly of said housing, opposed valves carried by said carrier, a sleeve rockably carried by said carrier, a shoulder carried by said sleeve, a pin slidable in said sleeve, and engaging at one end against said housing, a shoulder carried by said pin, and a spring disposed about said sleeve and a portion of said pin and engaging against said shoulders whereby to yieldably hold said carrier in a selected port closing position.

8. A valve comprising a housing provided with at least three fluid ports and a chamber common to all of said ports, a valve seat formed about at least two of said ports in said chamber, a valve carrier in said chamber, means swingably mount-

ing said carrier in said housing, said means including an operating lever projecting exteriorly of said housing, opposed valves carried by said carrier, a pair of opposed studs carried by said carrier, a sleeve rockably mounted on each stud, a shoulder carried by each sleeve, a pin slidable in each sleeve, and projecting outwardly of an end thereof, the projecting end of a pin rockably engaging said housing, a shoulder carried by each pin, and a spring about a sleeve and a portion of a pin and engaging between a shoulder on a sleeve and a shoulder on a pin, and normally holding said carrier in a selected port closing position.

GEORGE T. DOWNEY. 15
